UNITED STATES PATENT OFFICE.

JAMES LEWIS, OF MONTROSE, WEST VIRGINIA.

CHAIR.

1,083,215.

Specification of Letters Patent.

Patented Dec. 30, 1913.

Application filed December 30, 1912. Serial No. 739,386.

To all whom it may concern:

Be it known that I, JAMES LEWIS, a citizen of the United States, residing at Montrose, in the county of Randolph and State of 5 West Virginia, have invented a new and useful Chair, of which the following is a specification.

This invention relates to a chair and more particularly to one which is adapted to be 10 supported in an inclined position.

The object of the present invention is to provide means whereby the chair may be tilted and maintained in such position.

With the foregoing and other objects in 15 view which will appear as the description proceeds, the invention resides in the combination and arrangement of parts and in the details of construction hereinafter described and claimed, it being understood that 20 changes in the precise embodiment of the invention herein disclosed, can be made within the scope of what is claimed, without departing from the spirit of the invention.

In the drawings accompanying this specification and forming a part thereof, the preferable form of my invention is illustrated, in which:—

Figure 1 is a cross sectional view in elevation showing my improved chair. Fig. 2 30 is a similar view thereof showing the manner in which the chair is adapted to be used in the ordinary use thereof. Fig. 3 is a front view in elevation thereof.

Referring to the drawings in which similar reference numerals designate corresponding parts throughout the several views, 1 is the seat of a chair which is provided with the back 2 projecting upwardly therefrom. The chair is provided with the usual allotment of legs and rungs secured to the seat 1. Special mention however is made of the rung 6, which is the lower rung extending between the front legs of the chair. It is spaced a distance from the upper rung some- 45 what in excess of the usual spacing in order that it may provide a convenient rest upon which the feet are adapted to be placed. Hingedly secured to the lower surface of the seat 1 as at 10 is the leg 3 to the lower portion of which is secured the rack bar 4 which is adapted to engage the rung 5 of the chair. This rack bar is adapted to hold the auxiliary leg 3 in an extended position and also by reason of the hooked end upon the said 55 rack bar engaging the rung 6, is adapted to

hold the auxiliary leg 3 in a position substantially as illustrated in Fig. 2. Hingedly connected as at 8 to the front portion of the seat 1 is the second auxiliary leg 7 which is preferably provided adjacent its lower 60 end with a square portion through which extends the bolt 11 provided with the wing nut 12 thereon, the bolt and wing nut serving to clamp the extensible member 9. It is to be understood in this connection that the 65 member 9 is merely a plate or bar provided with a central extending slot therein in which travels the bolt 11.

From the foregoing it will be apparent that my improved chair may be used in the 70 ordinary manner and resting upon the four usual legs or it may be tilted to the position illustrated in Fig. 1 and supported in said position by means of the auxiliary legs 3 and 7. The degree of tilting is adjustable 75 by means of the rack bar 4 and the auxiliary leg 7 is by reason of the extension member 9, adapted to further hold the said chair in the desired position. It will therefore be seen that the tilted chair is held securely in its 80 tilted position, it not being able to tilt forward or backward. By reason of the spacing of the lower rung 6, the user may place his feet upon the forward rung and the chair will prove to be a most comfortable 85 and desirable one.

A somewhat modified form is illustrated in which the second auxiliary leg 7 is done away with and the extensible member 9 is secured directly to the front legs of the chair, 90 the result being practically the same as heretofore described. The chair so constructed is adapted to take the place of the chair which is usually tilted against the wall and is less liable to slip, it being apparent from 95 Fig. 1 that the center of gravity of the chair and the person sitting thereon will fall between the auxiliary legs and therefore the chair will be very stable. The entire construction is simple and may be attached to 100 an ordinary chair or similar structure.

Having thus fully described the construction and operation of my improved chair, what I claim to be new and original with me is:—

The combination with a chair, of an auxiliary leg hingedly secured to the rear central portion thereof, a rack bar secured thereto coating with one of the chair rungs adapted to hold the same in adjusted ex- 116

tended position, an extensible auxiliary leg hingedly secured to the front central portion of the chair, the two rear legs and the front and rear auxiliary legs forming a four-legged stable structure holding the chair seat in inclined position.

In testimony that I claim the foregoing as

my own, I have hereto affixed my signature in the presence of two witnesses.

JAMES LEWIS.
